UNITED STATES PATENT OFFICE.

WILLIAM BERNARD, OF NEW YORK, N. Y.

SIGHT FOR FIREARMS.

945,366.

Specification of Letters Patent. Patented Jan. 4, 1910.

Application filed March 27, 1908. Serial No. 423,718.

To all whom it may concern:

Be it known that I, WILLIAM BERNARD, a citizen of the United States, residing at the borough of Manhattan, in the county 5 of New York and State of New York, have invented a certain new and useful Improvement in Sights for Firearms, of which the following is a specification, reference being had therein to the accompanying drawings, 10 forming part thereof.

My invention relates to rear sights for fire-arms, of the type in which facilities are provided for adjusting the sight for various distances of firing and to compensate for the effect of the wind on the course 15 of the projectile.

The object of the invention is to produce an adjustable rear sight of simple and reliable construction in which the necessary 20 adjustments may be quickly and conveniently made, and without a multiplicity of operations, while the fire arm is held in convenient position.

To this end my invention consists in the 25 sight hereinafter described, and defined in the claims which follow.

I will now describe the embodiment of 30 my invention illustrated in the accompanying drawings, and will thereafter point out my invention in claims.

Figure 1 is a vertical longitudinal section of a sight embodying my invention. Fig. 2 is a rear view of the same. Fig. 3 is a plan view, with the upper portion of 35 the sight arm broken away. Fig. 4 is a detail vertical sectional view of the sight piece and the windage adjustment.

The illustrated embodiment of my invention is adapted particularly for use on military rifles, being attached to the top of the barrel in front of the breech, in the usual manner. It comprises a base portion 1, secured to the rifle, and a sight-piece carried at the end of an arm 2. This arm is pivoted 40 on the pivot pin 3, mounted in the upwardly extending flanges 4 on the base, so that it may be swung upward from horizontal position to vary the elevation of the sight in proportion to the distance for 45 which the sight is to be adjusted. The lower portion of the sight arm 2 is provided with two side members 5 which are enlarged at their lower ends to form ears 6, which

are journaled on the pivot pin 3. A segmental pinion 7 is journaled on the pivot 55 pin 3 between the ears 6. The pinion 7 and the arm 2 are normally connected, so as to move together upon the pivot pin 3, by means of the central portion 8 of the arm 2, which forms a stiff spring engaging a 60 surface on the pinion. A slight inclined projection 9 on the end of the spring 8 resiliently engages a corresponding depression in the surface of the pinion.

To adjust the sight for distance, the pinion and the arm are rotated more or less upon the pivot pin 3 by means of a knurled head 11 operating through suitable connections with the pinion. The head 11 is fixed to a screw 12 journaled in the flanges 4 and 65 confined against longitudinal movement. A nut 13 is mounted on the screw 12 and provided with a pivot pin 14 which engages the slotted portions of the arms 15 and 16 forming part of a bell-crank lever pivoted on a 70 pin 17 mounted on the base 1. The lever has an arm 18 which is slotted at the end to engage a pin 19 fixed in an arm 20 projecting from the rear end of a rack 21. The rack slides on the upper surface of the base 80 1 and engages the pinion 7.

By means of the connections just described, rotation of the knurled head 11 causes the rack to rotate the pinion 7 and thereby change the angular position of the 85 arm 2 carrying the sight to elevate the latter to the desired position.

To indicate the proper adjustment for distance of the sight, the arm 16 of the bell-crank lever is prolonged to form a pointer 90 22, and a scale 23 is provided on the upper surface of the rear end of the base, this surface being slightly beveled so that the scale may be visible from the rear of the sight and when the gun is held in firing position. 95 As the head 11 is turned and the arm 2 is raised, the pointer moves across the scale, which is graduated to conveniently designate the various distances of firing.

In order to quickly depress the sight from 100 the raised position shown in the drawings to the horizontal position, without rotating the head 11, a force may be exerted against the front of the arm to swing it backward, this force being enough to overcome the spring 105 8. The arm is thereby rotated independ-

ently of the pinion 7, which in the meantime, remains in the adjusted position. When the arm is lifted up again, it returns to the same adjusted position, the projection 5 9 once more engaging its corresponding depression in the pinion.

A grooved sight piece 24, constituting an open sight, is mounted upon the end of the arm 2, as shown in Fig. 4. The sight piece is shown as made cylindrical in form and the groove as cut on a curve concentric with the cylindrical surface of the sight piece so that the groove will be in line with the eye regardless of the inclination of the arm. To 10 render it adjustable laterally for windage, the sight piece is formed with a recess which receives the reduced portion 25 of the arm 2. An adjusting screw 26 journaled in the sight piece passes through a threaded hole in 15 the part 25 and is provided with a knurled head 27, by which it may be turned to cause the sight piece to move laterally. To denote the lateral adjustment of the sight piece, a graduated scale is provided on the lug 30 on the rear face of the arm 2.

A peep-sight is provided, comprising a lug 28 mounted on a sleeve 29 which is journaled on the end of the sight piece 24 and retained thereon by the upset end of the adjusting screw 26. The sleeve 29 is knurled so that the peep sight may be conveniently turned up in position for use, or turned down when an open sight is required. To properly adjust the peep-sight for the position corresponding to the angular position of the arm 2, a graduated scale is provided on the surface of the sight piece 24 as shown in Fig. 2.

The locations of the scales for the adjustment of the sight piece 24, the peep-sight 28 and the arm 2, respectively, are such that they may be seen while the gun is held in firing position. The adjusting members for the respective parts may also be conveniently manipulated in this position.

It is obvious that various modifications may be made in the embodiment of my invention herein described and illustrated in the accompanying drawings within the spirit 50 and scope of my invention.

What I claim is:

1. A sight comprising a base member fixed to the gun, an arm carrying a sight piece and pivotally mounted on the base member and extending rearwardly of the pivotal connection, and manually operable adjusting means for moving the arm upon its pivot comprising a rotary member journaled on a transverse axis on the base member.

60 2. A sight comprising a base member fixed to the gun, a sight piece adjustable for distance, adjusting means for raising and lowering the sight piece, a scale for distance on the rear end of the base member and visible from 65 the rear of the sight and an indicating mem-

ber moving horizontally over the scale and connected with the sight piece to indicate the adjustment thereof.

3. A sight comprising a grooved sight piece forming an open sight, a peep sight member rotatable about a transverse horizontal axis to move it into and out of coöperative relation with the grooved sight piece and manually operable means for laterally adjusting the grooved sight piece. 70

4. A sight comprising a cylindrical sight piece having a groove concentric therewith to form an open sight, and a peep-sight member rotatable about a transverse horizontal axis to move it into or out of coöperative relation with the grooved sight piece. 75

5. A sight comprising a sight piece, adjusting mechanism for adjusting the elevation of the sight piece, and connections between the sight piece and the adjusting mechanism constructed and arranged to permit the sight piece to be depressed and raised independently of the adjusting mechanism. 80

6. A sight comprising a sight piece, a pivoted arm upon which the sight piece is mounted, adjusting mechanism for rotating the arm about its pivot to adjust the elevation of the sight piece, and connections between the arm and the adjusting mechanism arranged and constructed to permit the arm 90 to be depressed and raised independently of the adjusting mechanism.

7. A sight comprising a sight piece, a pivoted arm upon which the sight piece is mounted, adjusting mechanism for rotating the arm upon its pivot to adjust the elevation of the sight piece, and resilient yielding connections between the arm and the adjusting mechanism to permit the arm to be depressed and raised independently of 100 the adjusting mechanism. 105

8. A sight comprising an arm pivoted on a horizontal axis, means for moving the arm about such axis to adjust the elevation of the sight, a horizontal graduated scale and a pointer moving horizontally about a vertical axis and connected with the arm so as to indicate on the scale the elevation of the sight. 110

9. A sight comprising a base member provided with two side flanges, an arm provided with a sight piece and pivoted between said flanges on a transverse horizontal axis, a pointer mounted on a vertical axis between said flanges, a scale on the base member co-operating with the pointer, and connections between the pointer and the arm to cause the pointer to move in unison with the arm to indicate the elevation of the sight piece. 115

10. A sight comprising a base member, an arm pivotally mounted on a transverse horizontal axis on the base member, means for moving the arm about such axis to incline the arm at any desired angle, a sight piece mounted on the arm and comprising an open 125

130

3

sight member and a peep sight member arranged to coöperate with the open sight member, and means for laterally adjusting the sight piece.

5 11. A sight comprising a sight piece, a pivoted arm upon which the sight piece is mounted, and adjusting mechanism for moving the arm upon its pivot to adjust the elevation of the sight, such mechanism in-

cluding a rack engageable with the pivoted arm and a bell crank lever adapted to move such rack.

In testimony whereof I affix my signature in presence of two witnesses.

WILLIAM BERNARD.
